UNITED STATES PATENT OFFICE

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS

MINING MACHINE

Application filed July 6, 1926. Serial No. 120,617.

This invention relates to improvements in mining machines and more particularly to improvements in the shortwall type of kerf cutting mining machine adapted to undercut 5 coal and form a kerf which is higher in vertical cross section nearer the working face than at the extreme inner margin of said kerf formed remote from the working face.

A prior application filed by Michael Har- 10 dick, on July 15, 1925, Serial Number 43,668, relates to a machine of the class above men- tioned.

The principal object of my invention is to provide an improved means for supporting 15 the cutting elements which discharge the cuttings from both cutter chains, to provide an improved driving mechanism for the cutter chains, and an improved means for adjusting the cutter chains after they have become 20 loosened from wear.

My invention may be best understood by reference to the accompanying drawings, wherein:—

Figure 1 is a top plan view of the device 25 embodying my invention.

Figure 2 is a fragmentary side view of the device illustrated in Figure 1; and

Figure 3 is a sectional view taken on line 3—3 of Figure 1.

Like numerals refer to like parts throughout the various figures.

In these drawings I have illustrated a mining machine of the shortwall type 10, comprising a main frame 11, having a motor 12 on the forward portion and the usual cutter chain drive gearing and feed mechanism with operating and controlling levers at the rearward portion. An underframe 13 is fixed beneath said main frame and is of large enough vertical dimensions to accommodate 40 two cutting elements which project forwardly from beneath said motor.

The aforementioned cutting elements comprise a main cutting element 14 which rests 45 in a guide shoe 15 and an auxiliary cutting element 16 spaced above said main cutting element by a guide shoe 17, but projecting forwardly from beneath the motor, only for a portion of the length of said first mentioned main cutting element. This feature causes the

mining machine to cut a horizontal kerf on the mine bottom which is relatively wide during a portion of the cut near the working face and narrow at the inner extremities of the cut. This causes the coal to easily roll away 55 from the face when shot down and produces a greater percentage of lump coal than could be had if a single narrow kerf were cut since less powder is needed to break the coal away 60 from the face and the force of the explosion will not break up the coal into small pieces.

The lower or main cutting element 14 comprises a forwardly projecting cutter bar 18 having a cutter chain 19 riding in guides 20, 20, thereon, and the upper or auxiliary cutting element 16 comprises a forwardly projecting cutter bar 21 having a cutter chain 22 riding in guides 23 thereon. The cutter chains 19 and 22 are simultaneously driven 65 by sprockets 24 and 25 respectively. Said sprockets are freely mounted on a vertical shaft 26 and adapted to be operatively connected or disconnected from said shaft by a single clutch 27 which in this case is a jaw 70 clutch. It may be noted that said sprockets are adapted to be connected together and in the construction shown are both integral with a hub 28. The shaft 20 is driven by the motor 12 through a suitable chain of gearing 75 common to mining machines of this class.

Referring now to the method of attaching and holding in alignment the cutter bars 18 and 21, it may be seen that said cutter bars are attached to the under portion of the main frame 11 and the upper portion of the under-frame 13 in the following manner:

A projection 29 integral with the main frame 11 projects down longitudinally from beneath said main frame and fits between the inner portion of the rails 30, 30 of the cutter bar 21. A guide and spacing shoe 17 has an upper projection 32 which fits between the rails 30, 30 of said upper cutter bar, a central portion 33 to vertically space said cutter bars at the proper distance, and a lower projection 34 which fits between the rails 35, 35 of the cutter bar 18. A supporting member and guide 15 is fastened to the upper portion of the underframe 13 and supports and aligns 80 the lower portion of the cutter bar 18 and 85 90 95 100

thus keeps the supporting means and cutting elements in alignment. Bolts 36, 36 having nuts 37, 37 thereon, pass through said supporting means to hold said cutting elements to the main frame and underframe. The heads of said bolts 36 bear against the bottom portion of the guide 15 while the nuts 37 bear against the upper portion of the main frame 11. This insures a rigid connection and accurate alignment of the cutting elements to the main frame and in addition stiffens the underframe and cutting elements and enables them to withstand lateral thrusts imposed upon them during cutting.

Means are also provided for adjusting the tension of each of the cutter chains to allow for wear of the chains. In the preferable form shown herein, means are provided so that both chains may be adjusted simultaneously or independently of each other. It is desirable that the additional provision be made whereby either chain may be adjusted independent of the other since the cutter chain on the main cutting element 14 does more work and is subjected to harder usage than the chain on the auxiliary cutting element 16 and therefore necessarily tends to wear and stretch sooner than the chain on the auxiliary cutter bar, and hence the main cutter chain must be tightened more often than the auxiliary cutter chain. To adjust said chains, I provide two adjusting screws 38 threaded through nuts 39 fixed to the cutter bar 21. The forward ends of said screws bear against the main frame 11. The rearward ends of the screws are provided with suitable heads which may be gripped by a wrench or other like device. Turning of the screw in one direction or tightening it causes said screw to bear against the main frame 11 and tends to push the cutter bar out when the nuts 37, 37 are released. Turning in the other direction or loosening releases the pressure of the screws on the frame and leaves the bar free to be pushed backwards to loosen the cutter chain. In order to adjust the tension of the cutter chain 19 as well as of the cutter chain 22, a block 40 is fixed between the rails 30, 30 of the cutter bar 21 and has a downward projection which abuts an upward projection on a similar block 41 fixed between the rails 35, 35 of the main cutter bar 18. A threaded hole 42 passes through the upper projection of the block 41 and is provided with a screw 43 threaded therein. Said screw bears against the projection of the block 40. Turning of the screw 43 in one direction tends to push the cutter bars apart while turning in the other direction allows the cutter bars to be pushed towards each other. It will thus be seen that simultaneous adjustment of both cutter bars may be obtained by loosening the nuts 37 and tightening the screws 38 or vice versa, and independent adjustment of the

cutter bar 18 may be obtained by means of the auxiliary adjusting screw 43.

Having thus described the various features of the embodiment of my invention shown herein, it will now be clearly seen that I provide a shortwall type of mining machine having two horizontally extending cutting elements vertically spaced beneath said mining machine motor in the space between the under portion of the main frame and the upper portion of the bottom of the underframe. The upper cutting element is shorter than the lower cutting element and a kerf is therefore formed which is higher in vertical cross section nearer the working face than at the extreme inner margins of said kerf formed remote from the working face. An improved means is provided for supporting and holding said cutting elements in alignment and an improved means is provided whereby the tension of both cutter chains may be easily adjusted simultaneously or independently. Both cutter chains are driven from a common drive shaft behind the motor and the cuttings may thus be expelled from beneath the motor and out behind and to the side of the mining machine.

Although I have illustrated and described one form in which my invention may be embodied, it will be understood that the construction and arrangement of the various parts may be altered without departing from the spirit and scope thereof. I do not therefore wish to be construed as limiting myself to the particular arrangement shown herein, excepting as it may be specifically limited in the appended claims.

I claim as my invention:

1. In a mining machine adapted to cut a horizontal kerf in a mine wall wider at the outermost extremities than at the innermost extremities, a motor, feed gearing and controlling mechanism rearward of said motor, a main forwardly extending cutter chain carrying kerf cutting element beneath said motor, an auxiliary cutter chain carrying kerf cutting element above said first named cutting element but beneath said motor and extending forwardly for a portion of the length of the first mentioned main cutting element, a plurality of chain driving sprockets extending beneath said motor and mounted on a common drive shaft rearward of said motor to simultaneously drive both of said cutter chains, and means for simultaneously adjusting the tension of said cutter chains.

2. In a mining machine adapted to cut a horizontal kerf in a mine wall wider at the outermost extremities than at the innermost extremities, a motor, feed gearing and controlling mechanism rearward of said motor, a main forwardly extending cutter chain carrying kerf cutting element beneath said motor, an auxiliary cutter chain carrying kerf cutting element above said first named cut-

ting element but beneath said motor and extending forwardly for a portion of the length of the first mentioned main cutting element, a plurality of chain driving sprockets extending beneath said motor and mounted on a common drive shaft rearward of said motor to simultaneously drive both of said cutter chains, and means whereby the tension of said cutter chains may be adjusted simultaneously or independently.

5 Signed at Chicago, in the county of Cook and State of Illinois, this 30th day of June, A. D. 1926.
